UNITED STATES PATENT OFFICE.

GEORGE W. BOWER, OF SCHENECTADY, NEW YORK, ASSIGNOR TO GENERAL ELECTRIC COMPANY, A CORPORATION OF NEW YORK.

CROSSOVER FOR OVERHEAD TROLLEY LINES.

Application filed October 30, 1922. Serial No. 597,753.

To all whom it may concern:

Be it known that I, GEORGE W. BOWER, a citizen of the United States, residing at Schenectady, county of Schenectady, State of New York, have invented certain new and useful Improvements in Crossovers for Overhead Trolley Lines, of which the following is a specification.

The present invention relates to electric street railways and more especially to overhead trolley systems by means of which electric power is supplied to the propelled vehicles.

In present day practice two species of overhead systems are employed. The single system utilizes a single overhead wire and a single current collector or trolley wheel and discharges the current to ground through the car wheels and track. The double system utilizes two independent overhead wires, one to supply the high potential current to the car and the other to receive the return current, and a double current collector or trolley making contact with both of the wires. The single system is in most general use, while the double system is used where it is impractical to install tracks in the roadway and has become known as the trackless trolley system, and is employed chiefly as an adjunct or feeder to roads operating on the single system.

The object of my invention is to provide guarded means for the points of crossing between double system trolley wires and two or more single system trolley wires, whereby the respective current collectors may be enabled to pass without danger of becoming displaced or of short circuiting the electric conductors operating under different potentials.

One embodiment of the invention is shown in the accompanying drawing in which:

Fig. 1 is a side elevation of a crossover device for the intersection of a double trolley system with two single trolley systems; Fig. 2 is an under side plan view; Fig. 3 is a perspective view thereof, and Fig. 4 is a perspective view of a double collector head for use in conjunction with the double trolley system.

The single system wires 1 and 2 are shown as usually suspended over the centers of the respective tracks of a double tracked street and their spacing apart is ordinarily about nine feet. The double system wires 3 and

4 are suspended over the trackless street and have a normal spacing of about fourteen inches. One of the wires 3 or 4 is charged with high potential current and the other with low potential current and both the wires 1 and 2 are charged with high potential current and accordingly it is very important that they be protected from the possibility of becoming short circuited with the low potential wire as by a flying trolley pole.

In the construction shown the wires 3 and 4 of the double trolley system are cut off a considerable distance back from the vertical planes of the single system wires 1 and 2 and their ends connected to the opposite ends of an insulated bridge structure 5, so that in case a single system trolley should escape from its wire 1 or 2, as it is about to cross the path of the double system wires 3 and 4, it cannot by any chance come in contact with any part electrically charged by the latter system.

The insulated bridge structure 5 is built up about two parallel beams of gas pipe 6 having their ends secured to crossbars 7 and 8, to the outer ends of which are attached insulating blocks 9 having at their outer ends metal clamping plates 10 to which the wires 3 and 4 are to be attached. The beams 6 have threaded thereon metallic brackets 11 and struts 12 which support at their lower ends the insulated track sections 13, 14 and 15. The brackets 11 are in the form of an inverted U to straddle the single system wires 1 and 2 and are provided near their upper ends with transverse mortises through which extend bars 15' carrying at their ends ears 16 for supporting the single system wires well up from the plane of the tracks 13, 14 and 15.

The trackless system employs a current collector as shown in Fig. 4 comprising two metal shoes 18, 19 insulated from each other by a guide bracket 20 of insulating material. In order that such a collector may pass uninterruptedly beneath the bridge structure 5 and without contacting with the single system wires 1 and 2 as it crosses beneath them, inclined guard planes 21 are arranged in the path of the bracket 20 on each side of the path of the single system wires so that when the contact shoes 18 and 19 pass the adjacent ends of the track sections 13, 14 and 15, the collector is prevented from rising up into the transverse space for the 110

wires 1 and 2 by reason of the upper edge 5 of the bracket 20 continuing in contact with the inclined plane 21 on the approaching side of the transverse space until the shoe 5 part is entirely across it. These inclined planes 21 may be formed of insulating slabs attached to the lower ends of the brackets 11 and near the upper ends of the adjacent struts 12 or end blocks 9 as shown in Figs. 10 1 and 2 or they may be made of stiff netting 22 as shown at the left of Fig. 3.

In order to condense the bridge structure as much as the conditions of use will permit, the spacing of the tracks for the trackless trolley is made less than the spacing of 15 the wires 3 and 4 by bowing them inwardly as best shown in Fig. 2.

The continuity of the conductors 1 and 2 over the bridge structure is accomplished by 20 means of insulated cables 23, 24 connected to the clamping plates 10 for the ends of the wires 3 and 4 and carried by the insulating blocks 9. These wires 23, 24 extend through the bores of the pipes 6 and are thereby effectively housed from injury.

The means for supporting the structure consists of hooks or eyes 25 mounted on the crossbars 8 and adapted to connect with the usual span wires 26.

30 While I have shown and described the best form of the invention known to me, I do not desire to be restricted thereto.

What I claim as new and desire to secure by Letters Patent of the United States, is,—

35 1. In a crossover for trolley lines, the combination of two beams having wire clamping plates connected to their ends through insu-

lation, sectional track members suspended beneath said beams and arranged to provide transverse passageways between their adjacent ends, and means for supporting crossing wires in said passageways.

2. In a crossover for trolley lines, the combination of two beams having wire clamping plates connected to their ends through insulation, sectional track members suspended beneath said beams and arranged to provide transverse passageways between their adjacent ends, means for supporting crossing wires in said passageways, and inclined 45 guards adjacent said transverse passageways.

3. In a crossover for trolley lines, the combination of two beams having wire clamping plates connected to their ends through insulation, struts and U-shaped brackets depending from said beams, insulating track sections supported by said struts and said brackets, means for supporting crossing wires between the arms of said brackets, and 55 inclined guards extending upwardly from the lower ends of said bracket arms.

4. In a crossover for trolley lines, the combination of a hollow beam having wire clamping devices connected to the opposite 65 ends thereof, insulated track members extending between said wire clamping devices and suspended beneath said beam, and an insulated electrical conductor connecting said clamping devices and extending through 70 said hollow beam.

In witness whereof, I have hereunto set my hand this 27th day of October, 1922.

GEORGE W. BOWER.
